G. F. STEEDMAN.

CLOSED HOPPER SAND BLAST.

APPLICATION FILED NOV. 22, 1912.

1,073,876.

Patented Sept. 23, 1913.

UNITED STATES PATENT OFFICE.

GEORGE F. STEEDMAN, OF ST. LOUIS, MISSOURI.

CLOSED-HOPPER SAND-BLAST.

1,073,876.

Specification of Letters Patent. Patented Sept. 23, 1913.

Application filed November 22, 1912. Serial No. 732,366.

To all whom it may concern:

Be it known that I, GEORGE F. STEEDMAN, a citizen of the United States, residing at St. Louis, Missouri, have invented a certain new and useful Improvement in Closed-Hopper Sand-Blasts, of which the following is a full, clear, and exact description, such as will enable others skilled in the art to which it appertains to make and use the same.

This invention relates to closed hopper sand blasts of the type illustrated and described in my prior Patent No. 979,897, dated December 27, 1910.

One object of my present invention is to provide a sand blast of the type referred to in which a single mechanism is provided for governing the sand-gate or valve that controls the supply of sand to the mixing chamber and the shut-off valve or throttle valve that governs the supply of sand and fluid pressure to the blast tool, and another object is to provide a closed hopper sand blast apparatus of simple construction which is so designed that the parts which are subjected to the greatest wear can be replaced easily and without the necessity of cutting rivets or other permanent fastening devices.

The figure of the drawings is a vertical sectional view of a sand blast apparatus constructed in accordance with my invention.

Referring to the drawings which illustrate the preferred form of my invention, A designates the closed sand supply hopper, B designates the mixing chamber, and 1 designates the sand-discharge opening through which the sand flows from the supply hopper into the mixing chamber. A shut-off valve or throttle valve C, preferably of soft rubber, is arranged in the mixing chamber so as to enable the flow of sand and air through the hose 2 that leads to the blast tool, not shown, to be stopped and started instantly at the will of the operator, and a sand-gate or valve D is provided for regulating the flow of sand from the supply hopper A into the mixing chamber B. The sand-gate or valve D is combined with the throttle valve C so as to enable a single actuating mechanism to be used for controlling both of said valves and also for caus-

ing communication between the sand supply hopper and the mixing chamber to be cut off automatically whenever the throttle valve C is closed. In the preferred form of my invention, as herein shown, the sand-gate D is detachably connected by means of removable fastening devices 3 to a casting 4 that carries the throttle valve C, and said plate is arranged in such a manner that it bears against and slides upon the top wall of the mixing chamber B. Any suitable mechanism can be used for actuating the connected valves C and D, the mechanism herein shown consisting of a manually-operated lever 5 provided with a spring-pressed ratchet 6 that cooperates with a ratchet plate 7 and links 8 and a connecting bar 9 for transmitting movement from the lever 5 to the rod or stem 10 of the throttle valve C, said rod projecting through a stuffing-box 11 in the end wall of the mixing chamber. By manipulating the lever 5 the sand-gate D can be arranged in different positions giving a greater or less opening for the sand, so as to accurately control the flow of sand from the supply hopper A into the mixing chamber, and when said lever is moved far enough to close the throttle valve C, as shown in the drawing, the sand-gate or valve D will have previously completely closed the sand-discharge opening in the bottom of the hopper and thus cut off communication between the hopper A and the mixing chamber B before the valve C closes its cooperating opening. The pawl and ratchet mechanism that cooperates with the lever 5 operates to hold the valves C and D in closed position. A stop 7a which is adjustably mounted in an elongated slot in the ratchet plate 7 acts as a stop to limit the outward movement of arm 5 and so controls the opening of valve D and the volume of sand passing into mixing chamber. In view of the fact that the sand-gate or valve D is arranged above the throttle valve C and closes in advance of same, said valve D protects the throttle valve C and prevents it from being subjected to constant abrasion by the sand that flows from the supply hopper into the mixing chamber, thereby greatly prolonging the life of the throttle valve C which is usually made of

soft rubber so as to insure a tight joint between the throttle valve and the sleeve 2^a to which the hose 2 is connected.

In addition to the desirable features 5 above-mentioned such a construction is inexpensive to manufacture and can be maintained at a low cost in view of the fact that the part which is subjected to the greatest 10 wear or abrasion from the sand, namely, the sand-gate D, consists of a small piece of sheet metal that is detachably connected to the throttle casting 4 in such a manner that it can be renewed easily. The throttle valve C is preferably made of soft rubber and is 15 removably carried on casting 4 so that it can be renewed readily. I also prefer to arrange a removable bushing 1^a in the top wall of the mixing chamber B, forming the sand-discharge opening that establishes communication 20 between the supply hopper and the mixing chamber, thereby enabling this part to be renewed easily when it becomes worn.

The filling hopper E which is arranged 25 above the sand supply hopper A is provided with an opening through which the sand flows into the supply hopper A, and a valve F is provided for normally closing said opening so as to cut off communication between the filling hopper E and the supply hopper A. The bottom of the filling hopper E is formed by a member 12 permanently connected to the side walls of the hopper E and a removable member 13 in which the outlet 30 opening of the filling hopper is formed, said removable member 13 preferably consisting of a substantially funnel-shaped casting that is clamped between the bottom member 12 of the filling hopper and a ring 14 on the top wall of the sand supply hopper A in such a manner that it can be removed easily by simply removing a few nuts or bolts that connect the bottom member 12 of the filling 35 hopper to the ring 14 on the supply hopper A. In the form of my invention herein shown the removable member 13 is provided at its upper end with a laterally projecting horizontal flange 13^a that lies between the parts 12 and 14, and screw-threaded studs 15 provided with nuts 15^a are used for connecting said parts together and thus clamping the member 13 in operative position, it being preferable to use a piece of packing 16 between the under side of the 40 member 13 and the ring 14 on the hopper A so as to insure an air-tight joint. The valve F is substantially cone-shaped and fits in a tapered seat formed in the lower end of the removable member 13, said member 13 being provided at its lower end with a depending flange or skirt 16^a of some suitable flexible or pliable material which is pressed against the valve F by the pneumatic pressure in the supply hopper, thus 45 insuring a tight joint. Any suitable means

may be used for actuating the valve F, the means herein shown consisting of a manually-operated rock shaft 17 provided with an arm 18 that is connected by means of links 19 to the valve F.

Having thus described my invention, what I claim as new and desire to secure by Letters Patent is:

1. In a sand blast apparatus, a sand supply hopper, a mixing chamber communicating with said hopper and provided with a discharge opening, a throttle valve in said mixing chamber for closing said discharge opening, and a sand-gate or valve for regulating the flow of the sand from the supply 75 hopper into the mixing chamber, said sand-gate being arranged between the throttle valve and the opening through which the sand enters the mixing chamber so as to protect the throttle valve in the mixing 80 chamber from abrasions caused by the sand flowing into the mixing chamber as the throttle valve is closing.

2. In a sand blast apparatus, a sand supply hopper and a mixing chamber connected together by means of an opening, a conduit 90 leading from said mixing chamber, a throttle valve in said mixing chamber for closing said conduit, and a plate arranged above said throttle valve and detachably connected 95 to same for controlling the flow of sand through the opening that establishes communication between the supply hopper and the mixing chamber.

3. In a sand blast apparatus, a mixing 100 chamber provided in its top wall with a receiving opening and in one of its end walls with a discharge opening, a throttle valve in said mixing chamber provided with a non-metallic end portion for cutting off 105 the escape of the material through said discharge opening, and a plate on said throttle valve arranged over the non-metallic portion of same for controlling the entrance 110 of the material through said receiving opening.

4. In a sand blast apparatus, a sand supply hopper having a top wall, a ring permanently connected to said top wall, a filling hopper arranged above same and provided at its lower end with a casting, means for detachably connecting said casting to said ring, and a removable member clamped between said casting and ring and provided with an opening through which the sand 115 flows from the filling hopper into the supply hopper.

5. In a closed hopper sand blast, a sand hopper, a removable mixing chamber detachably connected to the lower portion of 125 the sand hopper, the sand hopper being provided with a sand opening that establishes communication between the sand hopper and the top of the mixing chamber and the mixing chamber being provided with a 130

discharge opening to which the hose is connected, a sliding member to which a gate is connected that coöperates with the sand opening and regulates effective opening of the sand opening, and a flexible plug or valve carried by said sliding member that coöperates with the discharge opening in the mixing chamber and serves to close said discharge opening against the passage of air and sand or open same as may be desired, said gate being so arranged on the sliding

member with relation to the said plug or valve that the gate will completely close the sand opening before the plug reaches the discharge opening in the mixing chamber. 15

In testimony whereof I hereunto affix my signature in the presence of two witnesses, this 16th day of November 1912.

GEORGE F. STEEDMAN.
